The ornamental design for a point-of-purchase display stand, as shown.

DESCRIPTION

FIG. 1 is a front perspective view of a point-of-purchase display stand of my design;

FIG. 2 is a front elevational view thereof;

FIG. 3 is a rear elevational view thereof;

FIG. 4 is a left side elevational view thereof, the right side

elevational view being a mirror image thereof;

FIG. 5 is a top plan view thereof; and,

FIG. 6 is a bottom plan view thereof.
